US00D662256S

(12) **United States Design Patent**
Kluś

(10) **Patent No.:** **US D662,256 S**
(45) **Date of Patent:** **** Jun. 19, 2012**

(54) **EXTERNAL HOUSING FOR LED-BASED LINEAR LIGHTING APPARATUS**

(76) Inventor: **Sylwester Kluś**, Kamionka (PL)

(**) Term: **14 Years**

(21) Appl. No.: **29/405,664**

(22) Filed: **Nov. 4, 2011**

(51) **LOC (9) Cl.** **26-99**

(52) **U.S. Cl.** **D26/138**

(58) **Field of Classification Search** **D26/113, D26/71, 72, 73, 74, 75, 76, 78, 122, 121, D26/120, 119, 118, 1, 80, 86, 87, 88, 89, D26/90, 35, 36, 85, 62, 61, 63, 64, 65, 66, D26/67, 68, 28, 31, 24, 25, 26, 60, 103, 104, D26/105, 106, 109, 110, 93, 138, 140, 141, D26/142, 143, 144, 145, 152, 153, 154, 155, D26/41, 42, 51, 52, 50, 37, 128, 123, 124, D26/125, 129, 131, 134, 135, 136, 2, 3; D13/179, D13/180; D8/354, 382, 373, 377; 362/373, 362/294.02, 218, 510, 516, 410, 183, 396, 362/130, 190, 249.07, 249.09, 249.1, 249.11, 362/285, 413, 287, 220, 418, 419, 92, 249.08, 362/205, 184, 260, 399, 398, 397, 258, 374, 362/375, 216, 558, 561, 354, 249.06, 249.05, 362/132, 133, 249.03, 223, 241, 345, 327, 362/217.05, 247, 224, 297; 52/455; D25/124, D25/125, 60, 119; 349/113, 61, 59, 60, 62, 349/64, 65, 67, 66; 248/558, 339, 557; 438/15; 345/102; D12/406; D10/114.1, 111; D11/145, D11/144, 125, 121; 428/11; 257/96, 97, 257/98, 99**

(57) **CLAIM**

The ornamental design for an external housing of an LED-based linear lighting apparatus, as shown and described.

DESCRIPTION

FIG. 1 is a top perspective view of the external housing of an LED-based linear lighting apparatus showing the new design; FIG. 2 is a bottom perspective view thereof.

FIG. 3 is a front view thereof;

FIG. 4 is a side view thereof;

FIG. 5 is a top view thereof; and,

FIG. 6 is a bottom view thereof.
